J. R. BEERY,
MARKING STAKE,
APPLICATION FILED JUNE 9, 1915.

1,220,716.

Patented Mar. 27, 1917.

UNITED STATES PATENT OFFICE.

JOHN R. BEERY, OF CELINA, OHIO.

MARKING-STAKE.

1,220,716.

Specification of Letters Patent. Patented Mar. 27, 1917.

Application filed June 9, 1915. Serial No. 33,201.

To all whom it may concern:

Be it known that I, JOHN R. BEERY, a citizen of the United States, and a resident of the city of Celina, county of Mercer, 5 and State of Ohio, have invented certain new and useful Improvements in Marking-Stakes, of which the following is a specification.

My invention relates to improvements in 10 marking stakes designed for use particularly in plowing, fence building, seeding, etc., and has for its object the production of a stake of this character which will be of durable and economical construction and 15 efficient in use.

Other objects will appear hereinafter.

The invention consists in the combinations and arrangements of parts hereinafter described and claimed.

20 The invention will be best understood by reference to the accompanying drawing forming a part of this specification, and in which,

Figure 1 is a front elevation of a marking stake embodying the invention,

Fig. 2 is a side elevation thereof, and

Fig. 3 is a section taken on line $x-x$ of Fig. 1.

The preferred form of construction, as 30 illustrated in the drawing, comprises an elongated wooden body 1 which is square in cross section. The lower end 2 of said body is pointed to adapt the same to pierce the ground, and said end is reduced in 35 order to form a shoulder 3 adapted to serve as a stop to limit insertion into the ground, as will be readily understood.

Arranged at the upper end of the body 1 are designating plates 4 positioned one 40 above the other with their faces disposed at right angles to each other, said plates being secured to the stake body by means of a metallic strap 5. The ends of said strap are secured to opposite sides of the 45 stake body by securing devices 6, the central portion of said strap projecting upwardly from the stake and being formed to snugly embrace the plates 4, as clearly shown in Figs. 1 and 2. Securing devices 50 7 project through said plates and the opposite sides of strap 5 for securely locking the plates to said strap.

Arranged upon the body 1, intermediate the ends thereof, are handles 8 formed of 55 a single piece of wire secured to the stake body by means of wire fastening members

9 which engage loops or eyes 10 formed in the opposite sides of the wire from which the handles 8 are formed. The handles thus provided at opposite sides of the stake 60 afford ready means for carrying or transporting the same.

Provided at the lower end of the stake body is an eye 11 to which the marking or measuring rope or cord 12, used in conjunction with the stake, is adapted to be fastened, as clearly shown in Fig. 2.

A stake of the construction set forth is simple and economical in construction and hence may be manufactured at a low cost, 70 and the same is adapted to effectually serve in any connection where a marking stake may be used, as for instance in plowing, fence building, sowing seed, or surveying. The plates 4 may be painted different colors or upon the same may be placed directions or indications appropriate to the use to which the stake is to be put. For example, in surveying, the lines intersecting at the point where the stake is arranged 80 may be indicated upon the plates 4 to temporarily designate the same until permanent markings might be installed.

While I have illustrated and described the preferred form of construction for carrying my invention into effect, this is capable of variation and modification without departing from the spirit of the invention. I, therefore, do not wish to be limited to the precise details of construction set forth, 90 but desire to avail myself of such variations and modifications as come within the scope of the appended claims.

Having described my invention what I claim as new and desire to secure by Letters 95 Patent is:

1. A marking stake comprising a body; designation plates arranged one above the other at the upper end of said body and disposed angularly relative to each other; 100 and a strap having its ends secured to said body and having its central portion projecting upwardly from said body and formed to embrace said plates to securely fasten the same to said body, substantially as described.

2. A marking stake comprising a body; designation plates arranged one above the other at the upper end of said body and disposed angularly relative to each other; 110 and a strap having its ends secured to said body and having its central portion projecting

upwardly from said body and formed to embrace said plates; and means passing through said plates and the opposite sides of said strap for locking said plates to said strap, substantially as described.

3. A marking stake comprising a body; a vertically disposed designation plate having its lower edge resting upon the upper end of said body; and means for fastening 10 said plate to said body, said means comprising a strap having its ends engaging against opposite sides of said body and fastened thereto and having its central portion projecting upwardly and embracing said 15 plate, substantially as described.

4. A marking stake comprising a body; a vertically disposed designation plate having its lower edge resting upon the upper

end of said body; means for fastening said plate to said body, said means comprising 20 a strap having its ends engaging against opposite sides of said body and fastened thereto and having its central portion projecting upwardly and embracing said plate; and means passing through said plate and 25 the opposite sides of said strap for locking the parts together, substantially as described.

In testimony whereof I have signed my name to this specification in the presence 30 of two subscribing witnesses.

JOHN R. BEERY.

Witnesses:

W. E. TOUVELLE,
EDNA L. THEDIECK.
